UNITED STATES PATENT OFFICE.

CHARLES EDWARD CAMPBELL, OF LYNN, MASSACHUSETTS, ASSIGNOR, BY MESNE ASSIGNMENTS, TO LYNN COMMERCIAL REALTY CO., A CORPORATION OF MASSACHUSETTS.

ELECTRICAL SYSTEM.

Application filed October 23, 1919, Serial No. 332,733. Renewed February 10, 1926.

The present invention relates to electrical systems and more particularly to X-ray systems.

The use of X-rays for diagnosis or radiography requires considerable skill and experience. Among other prerequisites, all the adjustable parts must be exactly adjusted. In order to simplify the process, so that it may be performed by persons of ordinary skill, a number of short cuts have been proposed, among them a suggestion that all radiographs be taken with X-rays of the same degree of penetration. At least one of the adjustments is thereby ordinarily rendered unnecessary and the process simplified to that extent. Though ideal conditions are not thereby attained, it is possible, by suitable design, to reach a fair degree of approximation.

When it is desired to maintain a constant current flow through the X-ray tube, the carrying out of this suggestion is comparatively easy, for all that is necessary is to subject the tube terminals to a predetermined voltage. But not all objects can be satisfactorily radiographed with the same value of current flow through the tube.

An object of the invention is to provide an improved X-ray system, the X-rays generated by which shall have substantially the same degree of penetration irrespective of variations in the value of the current flowing through the tube.

As is well known, certain types of X-ray tubes are adapted for the passage therethrough of current flowing in one direction only, and will prevent the passage of current flowing in the opposite direction. If such a tube be directly connected to a source of alternating-current energy, therefore, part of the current wave will be prevented from flowing through. The alternating current supplied is thus rectified by the tube. The current which flows through is known as the useful current and the rest as the inverse current, and similarly with the voltages. The inverse voltage is thus naturally greater than the useful voltage and the difference between the two will vary with differences in the load.

As the inverse current and voltage produce no radiographic effect from the tube and as the degree of penetration of the X-rays and their volume are functions, respectively, of the useful voltage across the

tube terminals and the current flowing in the tube, it readily appears that the degree of penetration of the X-rays depends upon the useful voltage only and the volume of X-rays depends upon the useful current only. The greater the useful current, the greater will be the volume of X-rays emitted; but as an increased useful current naturally results in a decreased useful voltage, the X-rays emitted will be of less penetrating character. Similarly, if the useful current be decreased, the useful voltage will naturally become increased, with the result that the X-rays emitted, though of smaller volume, will be more penetrating. To maintain the penetration constant, therefore, provision must be made for increasing or decreasing the useful voltage accordingly as the useful current is decreased or increased.

To the attainment of the above-mentioned object, therefore, a feature of the invention resides in compensating for the changes in the useful voltage resulting from changes in the useful current, so that the useful voltage, and, therefore, the penetration of the X-rays, will remain substantially constant irrespective of changes in the useful current.

With the above and other objects in view, as will be apparent to persons skilled in the art, the invention consists in the improved X-ray system hereinafter described and defined in the appended claims.

In the accompanying drawings, Figure 1 is a diagrammatic view of an X-ray system embodying the invention; and Fig. 2 is a similar view of a modification.

The invention is illustrated in its preferred form in connection with an electronic X-ray tube and a high-potential transformer for exciting or generating X-rays in the tube, though it will be obvious that the invention is not limited to any particular type of tube or any particular exciting means. As is well known, the value of the current flowing in such a tube depends upon the degree of incandescence of the cathode filament. According to the preferred embodiment of the invention, therefore, the useful current is adjusted by adjusting the energy supplied to the filament. If the filament becomes more highly heated, for example, a greater useful current will flow through the tube, and a lower useful voltage across the tube terminals would naturally result. This would lower the degree of penetration of the

X-rays. Simultaneously with the increased heating of the filament, however, the voltage of the transformer is increased, which results in increasing the useful voltage across the tube terminals. This increase in the useful voltage compensates for the lowering in the useful voltage which would otherwise be caused by the increased heating of the filament. The useful voltage and, therefore, the penetration of the X-rays also, are thus maintained substantially constant.

In the preferred form of the invention which is illustrated in Fig. 1, the electronic type of tube is diagrammatically shown at 2 and comprises an anode 4 and a cathode comprising a filament 6. The anode is connected by a conductor 8 to an exterior terminal of the secondary winding 10 of a high-potential transformer 12. The cathode 6 is connected by a conductor 14 to the other exterior terminal of the secondary winding 10. The secondary winding 10 is preferably composed of two elements, as shown, the interior terminals of which are grounded by conductors 16 and 18, respectively, to a terminal 20 of the primary winding 22 of the transformer 12. By means of this arrangement of parts, the static strain between the tube terminals and the ground is approximately evenly distributed. An ammeter 20 is preferably connected in circuit with the conductor 18. The winding 22 serves also as the primary winding of another transformer, the secondary winding of which is indicated at 26, and is composed of very few turns. The winding 26 supplies the requisite energy for energizing the filament 6 through the adjustable resistance 27. The same winding 22 which operates to excite X-rays in the tube therefore operates also to heat the filament. The winding 26 is grounded to the secondary winding 10 by the conductor 14.

The terminal 20 of the primary winding 22 is connected by a conductor 28 to a terminal 30 of an auto-transformer 32. The other terminal 34 of the primary winding 22 is connected by a switch 36 and a switch 38 to the other terminal 40 of the auto-transformer 32. The switch 38 serves to connect the terminal 34 to any one of a number of taps 42, 44 and 46 (three only being illustrated) at the terminal 40 of the auto-transformer and the switch 36 is employed to close the circuit after the switch 38 has been suitably adjusted, thereby preventing arcing upon the switch 38.

The terminal 30 of the auto-transformer 32 is connected by a conductor 48, through a knife switch 50, to a line conductor 52. Any one of a number of taps 54, of the auto-transformer 32, may be connected, through a switch 56 and the switch 50 to a line conductor 58. The line conductors 52 and 58 are connected to any suitable source of al-

ternating-current energy, not shown. A voltmeter 60 is connected across the terminals 30 and 40 of the auto-transformer 32, for indicating changes in the voltage supplied to the auto-transformer from the line conductors 52 and 58.

In operation, the switch 50 is first closed to connect the auto-transformer 32 to the line conductors 52 and 58. Through suitable adjustment of the switch 56, the voltage of the auto-transformer, as indicated by the voltmeter 60, may be maintained substantially constant, irrespective of variations in the voltage of the source of energy (not shown) to which the line conductors are connected. If the voltage of the source is constant, this adjustment may be made once for all. The switch 38 is then closed. Normally, it may be assumed, the switch 38 is connected to the middle tap 44. The switch 36 is finally closed. If the switches 38 and 36 are closed in this order and opened in the reverse order, the arcing caused by the making and breaking of the circuit will take place upon the switch 36 alone, protecting the switch 38.

The auto-transformer will now supply alternating-current energy to the primary winding 22 of the high-potential transformer 12 and energy will be induced from the primary winding in the secondary windings 10 and 26, the winding 10 subjecting the tube terminals to a high voltage and the winding 26 supplying low voltage energy for heating the cathode filament 6. As explained above, one part of the current wave will be suppressed by the tube and unidirectional current only will flow in the tube. With this type of tube, therefore, the employment of a rectifier is unnecessary and the tube may therefore be directly connected to the transformer 12, as shown. The current in the tube is known as the useful current and the corresponding voltage is known as the useful voltage. It will readily appear that the switch 56 affords a means for compensating for variations in the voltage of the source of energy, so that the tube may be operated at a constant useful voltage though the system may be connected to sources of energy of different voltage. Operation of the tube at constant useful voltage is desirable when it is desired to employ X-rays of constant penetration. Not only the useful voltage, but the useful current is also thus maintained constant, for, once the switch 56 has been adjusted, the degree of incandescence of the filament is fixed, and it is the degree of incandescence of the filament which determines the value of the useful current flowing in the tube. The useful current being constant, the volume of X-rays emitted is constant. X-rays of constant penetration are thus emitted in constant volume.

Though it is possible to employ X-rays of constant penetration for radiographing a very large number of objects, the volume of the X-rays must be varied for some objects. For such objects, the useful current must be changed though, if X-rays of the same penetrating quality are desired, the useful voltage must be maintained constant. The change in useful current may be obtained by changing the degree of incandescence of the filament through suitable manipulation of the switch 38. The energy supplied to the filament depends upon the voltage of the filament winding 26, this voltage in turn depends upon the voltage of the primary winding 22 and this upon the adjusted position of the switch 38.

Assuming, for example, that the normal useful current flow through the tube, and the normal useful voltage across the tube terminals, are obtained when the switch 38 is connected to the tap 44 of the auto-transformer, and that it is desired to increase the value of the useful current, the switch 38 will be positioned so as to connect the primary winding 22 to the tap 42. The primary winding 22 will, of course, be subjected to an increased voltage, which will cause an increased voltage of the secondary winding 26. This, in turn, will cause the filament 6 to glow more brightly, which will cause an increased current flow in the tube. By reason of this increased flow of useful current in the tube, the useful voltage across the tube terminals would become decreased. But the winding 26 is controlled in accordance with the degree of energization of the same primary winding 22 which operates to excite X-rays in the tube, so that the increased voltage of the primary winding 22 will cause an increased voltage in the secondary winding 10. This increased voltage will compensate for the decrease which would otherwise take place in the useful voltage, so as to maintain the useful voltage constant. The penetration of the X-rays will thus be maintained substantially constant, but their volume will become increased. If the switch 38 be connected to the tap 46, on the other hand, the volume of X-rays will become decreased while maintaining constant the penetration of the rays. In practice, the number of taps 42, 44 and 46 may be as large as desired to provide for fine adjustments of the volume while maintaining the penetration of the X-rays constant.

The present invention therefore provides for radiographing a large variety of objects with rays of constant penetration and either constant or varying volume. The switch 56 and the voltmeter 60 afford a means for connecting the system to any desired source of energy so that rays of a predetermined penetration may be obtained

irrespective of variations in the energy of such source and the switch 38 affords a means for varying the volume of the rays without varying the predetermined penetrating quality of the rays.

It will be noted that in the system of Fig. 1, the filament winding 26 and the winding 10 become simultaneously energized upon the closing of the switch 36. The winding 10 immediately subjects the tube to a high voltage. The filament, however, cannot become heated to its maximum degree until after the lapse of a time interval. Until the maximum temperature of the filament is attained, the current flowing in the tube cannot reach its required maximum, normal value.

While X-rays of the desired penetrating quality are generated, therefore, they are not produced in the required volume until after the expiration of the time interval. Provision is accordingly made in the system of Fig. 2 for energizing the filament prior to subjecting the tube terminals to a high voltage, so that the filament may be permitted to reach its maximum degree of incandescence before any X-rays are generated. The filament winding 26 of this system is the secondary winding of a transformer 62 separate and distinct from the transformer 12 and having a separate primary winding 64. One terminal of the winding 64 is connected to the terminal 20 and the other terminal of the winding 64 is connected to the terminal 30 of the auto-transformer 32, through an adjustable resistor 66. The switch 38 is directly connected to the terminal 20 by a conductor 68. A switch 70 connects the terminal 34 of the primary winding 22 to the terminal 30 of the auto-transformer.

The switch 50 may be closed to connect the auto-transformer to the source of energy and the switch 56 may be adjusted to give the proper reading of the voltmeter 60, as before, to provide for the generation of X-rays of constant penetration. If the switch 38 is connected to one of the taps 42, 44 and 46, the primary winding 64 of the filament transformer 62 will become immediately energized. The degree of energization of the winding 64 may be adjusted through the resistor 66. The transformer 12, however, will remain deenergized until the closing of the switch 70. The voltmeter circuit will thus become energized and the filament 6 will thus become heated before the high-potential transformer 12 becomes operative to subject the tube terminals to a difference in potential. When the filament 6 becomes sufficiently heated, the switch 70 may be closed, whereupon the transformer 12 will become energized to excite X-rays in the tube. Adjustment of the switch 38 will result in simultaneous adjustment of the energy in the

transformers 12 and 62, so that the penetration of the rays may be maintained substantially constant, though their volume may be varied.

5 It will be understood that the invention is not restricted to the specific embodiments thereof which are herein illustrated and described, the principal claims are, therefore, broad in scope.

10 I claim:

1. An X-ray system having, in combination, an X-ray tube having a cathode and an anode, a transformer for exciting X-rays in the tube having primary and secondary 15 windings, said secondary winding comprising two elements, each having a pair of terminals, a source of energy to which said primary winding and one terminal of each of said elements is connected, 20 and means respectively connecting said other terminals to said cathode and said anode respectively.

2. An X-ray system having, in combination, an X-ray tube having an anode and a 25 cathode comprising a filament, a transformer for exciting X-rays in the tube having primary and secondary windings, said secondary winding comprising two elements, a terminal of one of which is connected to said 30 cathode and a terminal of the other of which is connected to said anode, an auto-transformer, means connecting one terminal of said primary winding and the other terminals of said elements to one terminal of 35 said auto-transformer, a switch adjustably

connecting the other terminal of said primary winding to the other terminal of said auto-transformer, a winding connected to said filament constituting the secondary 40 winding of a transformer for heating the filament, said primary winding constituting the primary winding also of said filament-heating transformer, a source of energy, and a switch adjustably connecting said auto-transformer to said source. 45

3. An X-ray system having, in combination, an X-ray tube having an anode and a cathode comprising a filament, a transformer for exciting X-rays in the tube having primary and secondary windings, said secondary 50 winding comprising two elements a terminal of one of which is connected to said cathode and a terminal of the other of which is connected to said anode, an auto-transformer, a switch connecting one terminal of said primary winding to one terminal of said 55 auto-transformer, a switch adjustably connecting the other terminal of said primary winding and the other terminals of said elements to the other terminal of said auto-transformer, a transformer for heating said filament having a primary winding connected to the first-named terminal of said auto-transformer and to said second-named switch and a secondary winding connected to said 60 filament, a source of energy for said auto-transformer, and a switch adjustably connecting said auto-transformer to said source. 65

CHARLES EDWARD CAMPBELL.
